SMOKER'S APPLIANCE

Charles H. Sapper, Hugh T. Kirkland, Hyman B. Lasting, and Joseph Elkin, Portsmouth, Va., assignors to Pressed Metals Commodities, Inc., Portsmouth, Va., a corporation of Virginia

Application May 28, 1934, Serial No. 728,014

6 Claims. (Cl. 131—51)

This invention pertains to an improved smoker's appliance of the general type of that constituting the subject matter of our co-pending application Serial No. 718,708, filed April 2, 1934.

5 An important object of the present invention is to provide a smoker's appliance embodying novel means for mounting said appliance in position on a card table or other support.

Another important object of the invention is 10 to provide an improved smoker's appliance comprising novel means for holding a package of cigarettes and either box or book matches.

A still further important object of the invention is to provide an appliance of the character 15 described embodying novel supporting means for a cup or the like.

Still another important object of the invention is to provide a smoker's appliance including an ash tray, together with novel means for detachably mounting said ash tray in a manner to permit the same to be conveniently removed for emptying or other purposes.

Still further objects of the invention are to provide a smoker's appliance of the aforementioned character which will be strong, durable, simple in construction, compact and which may be produced at comparatively low cost.

The foregoing and other objects of the invention will become apparent from a study of the 30 following specification, taken in connection with the accompanying drawings wherein similar reference characters denote like parts in the several views, and wherein:—

Figure 1 is a side elevational view of a smoker's appliance constructed in accordance with the present invention.

Figure 2 is a view in vertical longitudinal section through the invention.

Figure 3 is a rear elevational view of the device with the ash tray omitted.

Figure 4 is a detail view in perspective of the cup bracket.

Figure 5 is a view in vertical transverse section through the invention, showing the means 45 for supporting a cup thereon.

Figure 6 is a detail view in perspective of the main bracket.

Figure 7 is a detail view in top plan of the ash tray.

50 Figure 8 is a detail view in perspective of the upper jaw or clamp.

Figure 9 is a detail view in horizontal section, taken substantially on the line 9—9 of Figure 8.

Referring now to the drawings in detail, it will 55 be seen that the improved appliance comprises

a bracket which is designated generally by the reference numeral 1, said bracket including a vertical plate 2 with the upper end of which a right angularly extending jaw 3 is integral, said jaw 3 being engageable beneath the frame 5 of a conventional card table, a portion of the top of which is designated by the reference numeral 5. The jaw 3 is provided with upturned side flanges 6 which, it will be noted, engage the frame 4. At a point adjacent the plate 2, the jaw 3 is further provided with a slot 7, the purpose of which will be presently set forth.

The bracket 1 further includes a horizontal plate 8 which projects forwardly from the lower end of the plate 2, said plate 8 being integral 15 with the plate 2. Rising vertically from the free forward end of the plate 8 is a resilient plate 9 which is formed to provide shoulders 10. It will thus be seen that the bracket 1 is substantially U-shaped. A tongue 11 is struck from the vertical front plate 9. The reference numeral 12 designates a guide which is struck from the rear vertical plate 2 in a manner to provide a horizontal extension to the plate 9, said guide 12 having a slot 13 therein which is aligned with 20 the slot 7.

The reference numeral 14 designates a clamp which is slidably mounted in the slots 7 and 13. At its upper end, the clamp 14 terminates in a right angularly extending jaw 15 which is engageable over the table top 5 for coaction with the jaw 3 for removably mounting the appliance in position. At its lower end, the clamp 14 terminates in a forwardly projecting handle portion 16. The jaws 3 and 15 are yieldingly urged 35 toward each other by a suitable spring 17, one end of which is preferably connected to the jaw 3 and the other end of which is preferably connected to an intermediate portion of the clamp 14, as best seen in Figure 3 of the drawings. 40

Removably mounted on the bracket 1 is an ash tray 18 which is formed to provide a flange 19 which is engageable beneath the horizontal plate 8 of the bracket 1, said flange 19 having a recess 20 which accommodates the clamp 14. The flange 19 has formed thereon inturned side flanges 21 which are slidably engageable over the marginal side portions of the horizontal plate 8 for removably mounting the ash tray 18 on the bracket 1. A loop 22 is struck downwardly from a side portion of the flange 19. The loop 22 slidably receives a bracket 23 (see Figure 5) which includes an upturned, bifurcated free end portion 24 upon which a cup 25, or the like, is removably mounted. The cup 25 is mounted on the bracket 23 through 50 55

the medium of a headed stud 26 which projects from said cup and which is engageable between the bifurcations of the portion 24 of said bracket 23.

5 In use, the marginal portion of the table or other support is clamped between the jaws 3 and 15 in the manner illustrated to advantage in Figures 1 and 2 of the drawings. The handle 16 provides means for conveniently actuating the 10 upper jaw 15 relative to the lower jaw 3 against the tension of the spring 17. With the device thus mounted on the table or other support, a package 15 of cigarettes may be conveniently slipped between the plates 2 and 9 of the bracket 1, said cigarettes resting on the horizontal plate 8. A conventional box of matches may be slipped downwardly over the front plate 9 until arrested by engagement with the shoulders 10, the inner portion of the box being engaged and slid upwardly in a manner to expose the matches by 20 the tongue 11. Of course, the upper portion of the inner portion of the match box may be torn off to facilitate removal of the matches. If book matches are being used, the book may be conveniently wedged between the tongue 11 and the front plate 9. It will be noted that the ash tray 13 may be conveniently removed from the rest of the 25 appliance for emptying or other purposes and replaced. It will also be noted that, should it be desired, the cup bracket 23 may be removed from the rest of the appliance.

It is believed that the many advantages of an improved smoker's appliance constructed in accordance with the present invention will be readily understood, and although a preferred embodiment of the invention is as illustrated and described, it is to be understood that changes in the details of construction and in the combination and arrangement of parts may be resorted to 30 which will fall within the scope of the invention as claimed.

What is claimed is:—

1. A smoker's appliance of the class described comprising a bracket including opposed back and front plates for the reception therebetween of a package of cigarettes, a stationary jaw on the back plate, a slidable jaw on the back plate for coaction with the stationary jaw for detachably mounting the bracket on a support, resilient means yieldingly urging the jaws toward each other, the front plate being engageable in a box of matches for supporting said box on the bracket, and a tongue struck from the front plate for opening the box when it is mounted on said front plate.

2. A smoker's appliance of the class described comprising a bracket including spaced, opposed front and back plates and a horizontal plate extending therebetween, a stationary jaw integral with the back plate, a spring actuated jaw slidably mounted on the bracket and cooperable with the stationary jaw for detachably securing said bracket on a support, an ash tray, a flange projecting from the ash tray and engageable beneath the horizontal plate, means on the flange slidably engageable with the marginal side portions of the horizontal plate for removably mounting

the tray thereon, a cup bracket, and a loop on the tray flange for the reception of the cup bracket for removably mounting said cup bracket on the appliance.

3. A smoker's appliance of the class described comprising a bracket including a back plate, a horizontal plate projecting forwardly from the bottom of the back plate, a front plate rising from the horizontal plate, said front and back plates being adapted to receive a package of cigarettes therebetween, a stationary jaw projecting horizontally from the top of the back plate, said stationary jaw having a slot therein, a guide projecting from the lower portion of the bracket, a clamp slidably mounted in the slot and the guide, a jaw on one end of the clamp cooperable with the first-named jaw for mounting the bracket on a support, resilient means for yieldingly urging the slidable jaw toward the stationary jaw, a handle on the other end of the clamp for actuating the slidable jaw against the tension of the resilient means, an ash tray, and means for removably mounting the ash tray on the bracket.

4. A smoker's appliance of the class described comprising a bracket including a back plate, a horizontal plate projecting forwardly from the bottom of the back plate, a front plate rising from the horizontal plate, said front and back plates being adapted to receive a package of cigarettes therebetween, a stationary jaw projecting horizontally from the top of the back plate, said stationary jaw having a slot therein, a guide projecting from the lower portion of the bracket, a clamp slidably mounted in the slot and the guide, a jaw on one end of the clamp cooperable with the first-named jaw for mounting the bracket on a support, resilient means for yieldingly urging the slidable jaw toward the stationary jaw, a handle on the other end of the clamp for actuating the slidable jaw against the tension of the resilient means, an ash tray, and means for removably mounting the ash tray on the bracket, the last-named means including a flange projecting horizontally from the tray and engageable beneath the horizontal plate, and inturned flanges on the sides of the first-named flange engageable over the marginal side portions of the horizontal plate.

5. A smoker's appliance of the class described comprising a bracket including spaced, opposed front and rear plates for the reception therebetween of a package of cigarettes, means for mounting the bracket on a support, and an inclined tongue struck out from the front plate and cooperable with said front plate for mounting a book of matches on the bracket.

6. A smoker's appliance of the class described comprising a substantially U-shaped bracket adapted to hold a package of cigarettes, means for securing the bracket to a support, and a removable ash tray slidably mounted on the bight portion of said substantially U-shaped bracket.
